DRAFT RIGGING

Donald S. Barrows and Albert H. Lake, Rochester, N. Y., assignors to The Symington-Gould Corporation, Rochester, N. Y., a corporation of Maryland

Application March 29, 1939, Serial No. 264,832

11 Claims. (Cl. 213—71)

The invention pertains to draft riggings for railway vehicles and particularly to the connection between the coupler or drawbar stem and an associated yoke.

One of the objects of the instant invention is the provision, in a draft rigging, of a pivotal connection between the coupler and yoke, in which the parts may pivot freely but are held firmly against relative longitudinal movement to thereby minimize slack in the connection and increase the effectiveness of the draft rigging to such an extent that draft or buffing forces applied to the coupler will be transferred without lost motion to the cushioning unit.

Another object of the invention is the provision, in a draft rigging, of an adjustable means in a pivotal coupler-yoke connection, to thereby compensate for wear in the connection which may result from continued use.

An additional object of the invention is the provision, in a railway draft rigging, of a universal connection between the drawbar or coupler and the associated yoke in order to permit the coupler to move freely in a vertical or horizontal direction with respect to the yoke as well as rotate on the longitudinal axis of the draft rigging in order to compensate for any service movements of the coupler head from or on the longitudinal axis of the draft rigging to which the coupler may be subjected.

A further object of the invention is the provision, in a draft rigging, of a yoke having a transverse web or wall portion and a hood portion projecting forwardly therefrom, the hood portion being provided with a forwardly opening aperture having a shank or stem portion of an associated coupler extending therethrough, the stem portion of the coupler being formed with lateral extensions positioned inwardly of the hood when in assembled position and in bearing relation with inner surfaces of the hood for the transmission of draft forces from the coupler to the yoke, a removable bearing block positioned within the hood in bearing relation with the rear portion of the coupler for the transmission of buffing forces from the coupler to the yoke, and an adjustable means interposed between the bearing block and transverse web so as to compensate for wear in the coupler-yoke connection which may result therein from the continued use thereof.

These and other objects will become apparent from the following description considered with the accompanying drawings which form a part

of the present specification to illustrate exemplary forms of the invention and wherein:

Figure 1 is a side elevational view illustrating a portion of the draft rigging embodying a form of the invention.

Figure 2 is a fragmentary plan and sectional view of the disclosure illustrated in Figure 1, taken along the lines 2—2 of Figure 4.

Figure 3 is a longitudinal sectional view taken along the lines 3—3 of Figure 2.

Figure 4 is a view partially in end elevation and in section, taken along the lines 4—4 of Figure 2.

Figure 5 is a modified form of the invention illustrated partially in plan and in section to more clearly disclose the specific structure.

Figure 6 is a longitudinal sectional view taken along the lines 6—6 of Figure 5.

Figure 7 is a view taken along the lines 7—7 of Figure 5.

Figure 8 is a fragmentary plan and sectional view disclosing a further modification of the invention.

Figure 9 is a longitudinal sectional view taken along the lines 9—9 of Figure 8.

Figure 10 is a fragmentary end elevation and sectional view taken along the lines 10—10 of Figure 8.

Referring now in detail to the drawings, wherein like reference characters indicate like parts, and initially considering the disclosures of Figures 1 to 4, inclusive, the yoke, generally designated as 1, comprises spaced arms 2 adapted to embrace a cushioning mechanism (not shown). The yoke 1 is illustrated as being of the vertical type, that is, the arms 2 are positioned in longitudinally extending, spaced horizontal planes, but it will be understood, however, that the arms may be rigidly united to the side walls of the hood so that the arms would then extend in spaced vertical planes if desirable. The arms are connected together adjacent their forward portions by an intermediate web or transverse wall 3 formed integrally with said arms and providing an abutment or bearing member adapted to engage the forward portion of the cushioning mechanism for the transmission of buffing forces thereto.

Forming a portion of the yoke 1 is a hood 4 which projects forwardly from the web or wall 3 and is provided with a forwardly opening aperture 5 positioned on the longitudinal axis of the draft rigging for the reception of a stem or shank portion 6 of an associated coupler 7, the rear portion only of which is illustrated. The aper-

ture 5 is of sufficient dimensions to provide adequate clearance between the coupler stem and hood so as to permit the unrestricted universal movement of the coupler with respect to the yoke through the range of movement required under all normal conditions of service. In the instant structure the hood portion is preferably provided with a top wall 8, side walls 9 and a bottom wall 10 integrally connected to the yoke arms 2 and web 3 and, in order to permit the assembly or disassembly of the coupler and yoke, the lower portions 11 of the side and bottom walls are formed as an integral, substantially U-shaped, member which is adapted to be removably secured to the remaining integral portion 12 of the hood in interlocked relation thereto, as will be hereinafter more fully described. The juncture between the removable and integral portions 11 and 12, respectively, extends through the side walls 9 of the hood desirably in a horizontal direction substantially on the longitudinal axis of the hood so as to bisect the aperture 5 and then through the side walls 9 and bottom wall 10 in a vertical direction intermediate the extreme front portion of the hood and the transverse web 3.

The integral portion of the hood 12 and the removable portion 11 are restricted against unwarranted vertical separation primarily by means of laterally spaced bolts 13 extending through vertically aligned apertured shoulders 13^a and 13^b provided on the integral and removable portions respectively, while the portions are partially restricted against longitudinal separation by means of laterally spaced bolts 14 extending through aligned apertures provided in the lugs 14^a and 14^b which project downwardly from the integral and removable portions respectively. Shear or retaining lugs 15 provided on the upper and inner corners of the removable portion 11 extend into complementary slots 15^a formed in the integral portion 12 so as to assist in restricting the longitudinal separation of the portions and to diminish the tensional stresses in the bolts 14 and the shear stresses in the bolts 13 which will result therefrom from the application of draft forces to the coupler.

To transmit draft forces from the coupler 1 to the yoke 1 the stem has, adjacent the rear extremity thereof, an enlarged portion or lateral extension 16 positioned within the hood and provided with a convex surface 17 in bearing relation and concentric with a concave surface 18 formed on the inner surface of the hood and surrounding the aperture 5. The surfaces 17 and 18 are preferably spherical in form and concentric with respect to one another. Thus, when the coupler is moved, during service, in a vertical or horizontal direction the coupler stem and yoke will, by reason of the concentricity of the surfaces 17 and 18, maintain a surface contact at all times and thereby provide an adequate bearing area between the coupler stem and yoke for the transmission of draft forces.

The rear extremity 19 of the coupler stem 6, 65 formed preferably with a spherically disposed surface 20 which is concentric with the surfaces 17 and 18, is retained on the longitudinal axis of the draft rigging by means of an upper lug 21 depending from the top wall 8 of the integral portion 12 and an oppositely disposed lower lug 22 upstanding from the bottom wall portion 10 of the removable portion 11. Both of the lugs 21 and 22 are preferably spaced inwardly of the lateral extension 16 intermediate the front por-

tion of the hood and the vertical axis of the spherically disposed portion 20 in order to assist in the transmission of draft forces from the coupler to the yoke in addition to resisting the leverage action of the extremity 19 of the coupler stem. The lugs 21 and 22 are provided with concave, preferably spherical, surfaces 23 and 24, respectively, which are concentric with the rear surface 20 of the coupler stem so as to present additional surface engagements between the coupler stem and yoke during all movements of the coupler from the normal longitudinal axis of the draft rigging and thereby increase the bearing area between the coupler and yoke.

A removable thrust or bearing block 25, positioned between the rear extremity 19 of the coupler stem and transverse wall 3 of the yoke, is provided with a concave spherical surface 26 which is concentric and in bearing relation with the arcuate surface 20 of the rear portion 19, thereby permitting universal movement of the coupler as well as providing an adequate bearing area between the coupler stem and bearing block for the transmission of buffing forces. The bearing block, which is adapted to be adjustably movable longitudinally of the draft rigging, is further provided with a rearwardly extending dowel 27 which projects into an associated aperture 28 in the web 3 thereby acting as a guiding means in addition to retaining the bearing block on the longitudinal axis of the draft rigging.

In order to compensate for slight manufacturing tolerances in the elements forming the present structure, as well as for wear which may result in the various parts from the continued use thereof, shim plates 29 are interposed between the web 3 and the bearing block 25, which will control or substantially eliminate the slack or longitudinal movement of the coupler with respect to the yoke by retaining the block in a predetermined position longitudinally of the draft rigging. By the application of the shim plates 29 it will be readily observed that an adjustable means has been provided whereby the convex surface 20 of the stem extremity 19 may be retained, both during buffing or draft actions, in bearing relation with the convex surface 26 of the bearing block 25 and the concave surfaces 23 and 24 of the lugs 21 and 22, respectively. The adjustable positioning of the block 25 by means of the shim plates 29 also affords a substantially constant bearing relation between the surfaces 17 and 18.

Referring now in detail to the modified structure disclosed by Figures 5 to 7, inclusive, the yoke or yoke-acting means, generally designated as 1^a, comprises a pair of vertically spaced arms 2^a adapted to be connected to a cushioning mechanism (not shown) in any desirable manner for the transmission of draft forces thereto. It is not the intention to limit the present structure to a vertical disposition of the arms 2^a, and for this reason it will be understood that the arms may equally as well be positioned horizontally.

The arms 2^a are connected at their forward extremities by a transverse wall or web 3^a positioned intermediate the ends of the yoke 1^a forming an abutment or bearing member for the cushioning unit. The wall or web 3^a also forms a reinforcing member which retains the arms 2^a in spaced relation as well as being adapted to transmit buffing forces to the cushioning unit. The forward portion of the yoke 1^a is preferably formed as an integral hood 4^a comprising a top

wall 8^a, spaced side walls 9^a and a bottom wall 10^a which project forwardly from the web 3^a, said hood being provided with a forwardly opening aperture 5^a adapted to receive the stem portion 6^a of a coupler 7^a, the rear portion only of which is illustrated. The hood 4^a of the present modified structure differs somewhat from the hood 4 of the previously described structure in that, instead of being formed of two pieces, it is desirably formed as a unitary member integral with the web 3^a and arms 2^a. It will, however, be understood that if so desired the two-piece hood 4 may be substituted for the unitary hood 4^a, as it is not the present intention to limit each disclosure to the specific associated constructions as illustrated.

The coupler stem 6^a is provided with oppositely disposed lateral extensions 16^a positioned adjacent the rear extremity thereof and inwardly of the hood 4^a when assembled with the yoke 1^a so as to engage the inner portion of the hood for the transmission of draft forces from the coupler to the yoke. In order to permit the outer portion of the coupler or coupler head to move in a vertical or horizontal direction from the normal longitudinal axis of the draft rigging and still maintain a full surface bearing relation between the extensions 16^a and the hood, convex spherical surfaces 17^a, formed on the extensions 16^a, are made preferably concentric with concave spherical surfaces 18^a on the top and bottom walls 8^a and 10^a, respectively, which partially define the aperture 5^a inwardly of the hood.

The aperture 5^a, as will be observed by referring particularly to Figures 5 and 6, is of sufficient dimensions to allow suitable clearance between the coupler stem and hood 4^a so as to permit the unrestricted universal movement of the coupler with respect to the yoke. The aperture 5^a is preferably formed elongated, that is, a greater amount of clearance is provided between the sides of the coupler stem and the side walls 9^a of the hood than is normally required for the free movement of the coupler during service. The purpose of elongating the aperture 5^a is to facilitate the assembly of the various parts employed in the coupler-yoke connection.

To assemble the coupler with the yoke, the coupler is rotated axially or on its longitudinal axis through an arc of 90 degrees from normal position in order to position the lateral extensions 16^a horizontally. The coupler stem is then aligned with the aperture 5^a and moved rearwardly until the extensions 16^a are within the hood, at which time the coupler is rotated back to its normal position. The coupler and yoke will then be restricted against longitudinal separation by reason of the extensions 16^a engaging the top and bottom walls of the hood.

The rear extremity 19^a of the coupler stem, being spherically disposed, has a convex surface 20^a preferably concentric with the surfaces 17^a and 18^a, thereby forming, as in the previously described structure, all of the arcuate surfaces about a common center in order to permit the free universal movement of the coupler with respect to the yoke and associated parts, the latter of which will be hereinafter described.

Positioned in arrear of the extremity 19^a of the coupler stem and acting as a medium for the transmission of buffing forces from the coupler to the yoke is a bearing or thrust block 25^a which is adjustably movable longitudinally of the hood. The bearing block, inserted into the hood through the aperture 5^a and removably secured therein, is

formed with a forwardly opening concave spherical surface 26^a concentric with and adapted to engage the convex surface 20^a of the coupler stem. The block 25^a further functions as a support for the extremity 19^a for the purpose of retaining the rear portion of the coupler stem substantially on the longitudinal axis of the draft rigging thereby resisting the leverage action of the extremity 19^a of the coupler stem during movements of the coupler from the normal longitudinal axis thereof. The block 25^a is restricted against vertical displacement in an upward direction by the guide or positioning lug 21^a which depends, inwardly of the hood, from the top wall 8^a and in a downward direction by the guide or positioning lug 22^a upstanding within the hood from the bottom wall 10^a, while horizontal displacement of the block is restricted by the spaced side walls 9^a of the hood.

An adjustable wedge 30, also inserted into the hood through the aperture 5^a, is interposed between the block 25^a and the transverse web 3^a for the transmission of buffing forces from the coupler and block to the yoke. The wedge 30, adapted preferably to move in a vertical direction, is provided with an inclined forward face 31 in bearing relation with a similarly inclined face 32 on the block 25^a so as to move the block to such a position longitudinally of the draft rigging that the slack in the coupler-yoke connection will be controlled or, in other words, prevent movement of the coupler in a longitudinal direction with respect to the yoke.

Forming a positive means for retaining the wedge 30 in a predetermined or desired position, a bolt 33, which is inserted into the hood through the aperture 34 in the top wall, has a head portion 35 engaging the top portion of the wedge to restrict the upward movement of the wedge. The stem 36 of the bolt, extending through a vertically disposed aperture 37 in the wedge and an aligned aperture 38 in the bottom wall 10^a, is provided with a nut 39 on the free end thereof which is in bearing relation with the bottom wall 10^a. A compression spring 40 encircling the bolt stem is interposed between the bottom wall 10^a and the bottom portion of the wedge in order to retain the wedge in an elevated position against the bolt head 35.

It will be observed that, by a manipulation of the nut 39 so as to shorten the effective length of the bolt 33, the wedge 30 may be urged downwardly and, by reason of the inclined faces 31 and 32 on the wedge and block, respectively, the block 25^a may be urged forwardly in a longitudinal direction. By thus predetermining the vertical location of the wedge 30, and consequently the horizontal location of the block 25^a, the surfaces 26^a and 20^a, as well as the surfaces 17^a and 18^a, can at all times be easily retained in bearing relation and thereby provide an adjustable means to compensate for wear in the connection which may result therein from continued use. Apertures 41 are provided in the bottom wall 10^a of the hood for the inspection of the various parts within the hood as well as for the escape of any foreign substance that may enter the hood through the apertures 5^a or 34.

Considering now in detail the modified form of the invention illustrated in Figures 8 to 10, inclusive, the yoke or yoke-acting means, generally designated as 1^b, is somewhat similar to the previously described yoke 1^a and comprises vertically spaced longitudinally extending arms 2^b adapted to have interposed therebetween a cushioning

unit (not shown) which is connected to the arms 2^b by any of the numerously known methods.

As in the preceding structures, the arms 2^b are connected together by an integrally formed transverse web or wall 3^b positioned intermediate the ends of the yoke and forming a bearing or buffing member for the transmission of buffing forces to the cushioning unit.

Forming the front portion of the yoke 1^b is a hood 4^b extending outwardly of the transverse web 3^b preferably integral with the arms 2^b and the web 3^b to form therewith a single unitary structure. The hood 4^b in the instant structure is also formed as a unitary member comprising a top wall 8^b, spaced side walls 9^b and a bottom wall 10^b which, at their forward extremities, define an elongated aperture 5^b adapted to accommodate an associated shank or stem portion 6^b of a coupler 7^b, the rear portion only of which is illustrated.

Disposed on opposite sides of the coupler stem 6^b and positioned adjacent the rear extremity thereof, are extensions 16^b projecting laterally of the coupler stem within the hood 4^b and adapted to engage inner portions of the hood for the transmission of draft forces applied to the draft rigging from the coupler to the yoke. The lateral extensions 16^b are provided with convex spherical surfaces 17^b in bearing relation and preferably concentric with juxtaposed concave spherical surfaces 18^b which are formed on the top wall 8^b and bottom wall 10^b, respectively, and partially define the aperture 5^b inwardly of the hood. Thus, by reason of the concentricity of the surfaces 17^b and 18^b, the coupler will be permitted to move with respect to the yoke in a vertical or horizontal direction as well as rotate torsionally.

The portions of the top and bottom walls defining the aperture 5^b are spaced from the coupler stem an amount sufficient to provide ample clearance therebetween for the coupler to move in a vertical direction from the normal longitudinal axis of the draft rigging through the normal range of displacement to which the coupler may be subjected in service. The portions of the side walls 9^b defining the aperture 5^b are spaced from the sides of the coupler stem a greater amount than that required for clearance necessary to permit the unrestricted horizontal movement of the coupler from the normal longitudinal axis of the draft rigging. The purpose of thus forming the aperture 5^b elongated is to facilitate the introduction of the rear extremity of the coupler stem to within the hood, which may be accomplished by rotating the coupler on its longitudinal axis through an arc of 90 degrees from its normal position so as to dispose the lateral extensions 16^b in a horizontal direction. The coupler stem is then aligned with the aperture 5^b and moved rearwardly until the extensions are within the hood, at which time the coupler is returned to its normal position thereby disposing the extensions in a vertical direction adapted to engage the top and bottom walls of the yoke and prevent the longitudinal separation of the coupler and yoke, as most clearly illustrated in Figure 9 of the drawings.

The rear extremity 19^b of the coupler stem 6^b is formed with a spherically disposed surface 20^b preferably concentric with the surfaces 17^b and 18^b and in bearing relation with a concentric concave spherical surface 26^b provided in a thrust or bearing block 25^b positioned in arrear of the coupler stem within the hood. The thrust or bearing block 25^b, which is introduced into the

hood through the aperture 5^b, forms a means of retaining and supporting the extremity 19^b on the longitudinal axis of the draft rigging during all movements of the coupler, in addition to transmitting buffing shocks from the coupler to the yoke. As in the previously described modified structure, the block 25^b, which resists the leverage action of the extremity 19^b of the coupler stem, and is adjustably movable longitudinally of the hood, is restricted against vertical displacement in an upward direction by means of the guide or positioning lugs 21^b which depend inwardly of the hood from the top wall 8^b and in a downward direction by guide or positioning lugs 22^b upstanding from the bottom wall 10^b toward the block, while horizontal displacement of the block is restricted by the spaced side walls 9^b of the hood.

In order to control the slack in the coupler-yoke connection or, in other words, to compensate for wear in the connection which may result from continued use thereof and thereby retain the bearing surfaces of the coupler stem, hood and bearing block in contact relation at all times to prevent the longitudinal movement of the coupler with respect to the yoke, a wedge 30^a is interposed between the block 25^b and the transverse web 3^b. The wedge 30^a, which is also introduced into the hood through the aperture 5^b, further functions as a means for transmitting buffing shocks applied to the coupler from the block 25^b to the web 3^b. To provide for the adjustable longitudinal movement of the block 25^b in order to retain a connection between the coupler and yoke, free from slack, the wedge 30^a, which is adapted to move preferably in a vertical direction, has the forward face 31^a thereof inclined and in bearing relation with a similarly inclined face 32^a formed on the block, as most clearly illustrated in Figure 9.

The wedge 30^a is urged in an upward direction, tending to urge the block horizontally by reason of the inclined faces 31^a and 32^a, by means of the compression spring 40^a which extends into a vertically disposed pocket 37^a provided in the wedge. The spring is introduced into the pocket 37^a through an aperture 38^a in the bottom wall 10^b of the hood and retained therein by a suitable spring cap 42 which occupies the aperture 36^a and is formed with a positioning boss 43 extending within the spring.

The aperture 38^a, defined by an annular web 44 projecting downwardly from the bottom wall 10^a, is provided with a plurality of intermittently spaced aligned apertures 45 and 46, the horizontal axes of the aligned apertures 45 being at a higher elevation than, and at right angles to, the horizontal axis of the aligned apertures 46. The spring cap 42 is also provided with horizontally disposed apertures 47 and 48 having their axes also disposed in spaced vertical elevations and at right angles to each other, the purpose of which is to position the spring seat in various elevations and thereby restore the initial compressive value in the spring 40^a as the wedge 30^a moves upwardly as the result of the horizontal movement of the block required to compensate for any wear which may result in the connection. The spring seat is retained in a predetermined position by means of a pin 49 which may extend through the apertures 43 in the spring seat and aligned apertures 46 in the web 44 for retaining the spring seat in its lowermost position. As the wedge 30^a moves upwardly the pin 49 may then be removed and the spring seat is aligned with

the apertures 45 in the web, as shown most clearly in Figures 9 and 10, at which time the pin may then be reinserted into the aligned apertures 48 and 45, thereby retaining the spring seat at a higher elevation than in the previously described position and consequently restoring the initial compressive value in the spring. The spring seat may be retained at a higher elevation by aligning the aperture 47 in the spring seat with the oppositely disposed apertures 46 in the web 44, and at a still higher elevation by aligning the aperture 47 in the spring seat with the apertures 45 in the web 44.

It will be observed, from the preceding description, that a connection has been provided between a coupler and yoke in a railway draft rigging that minimizes slack in the connection or effectively reduces the longitudinal movement of the coupler with respect to the yoke, and thereby consequently increases the effectiveness of the draft rigging to such an extent that the draft or buffing forces, when applied to the coupler, will be transferred without lost motion to the cushioning unit. It will be further observed that a universal connection has been provided between a coupler and yoke in order to compensate for all movements that the coupler may be subjected to in service.

It will, of course, be understood that merely exemplary forms of the invention have been illustrated and described and that various alterations, changes and rearrangements of parts may be made to the disclosed structures without departing from within the scope of the appended claims.

We claim:

1. In a railway draft rigging, in combination, a yoke having a transverse wall and a hood portion projecting outwardly from said wall, said hood portion having a forwardly opening aperture defined by an inner concave spherical surface and intermediate concave spherical surfaces spaced from said inner surface, a coupler stem projecting through said aperture adapted to move universally with respect to the yoke and provided with lateral extensions in bearing relation with said inner concave surface and a rear convex spherical surface in bearing relation with said intermediate concave surfaces, and a removable bearing block interposed between said coupler stem rear surface and transverse wall.

2. In a railway draft rigging, in combination, a yoke having a transverse wall and a hood portion projecting outwardly from said wall, said hood portion having a forwardly opening aperture defined by an inner concave spherical surface and intermediate concave spherical surfaces spaced from said inner surface, a coupler stem projecting through said aperture adapted to move universally with respect to the yoke and provided with lateral extensions having surfaces concentric and in bearing relation with said inner concave surface and a rear convex spherical surface in bearing relation with said intermediate concave surfaces, a bearing block provided with a concave spherical surface in bearing relation with the rear convex surface of said coupler stem, and means interposed between said bearing block and transverse wall, in order to retain said bearing block in a predetermined position longitudinally of said draft rigging.

3. In a railway draft rigging, in combination, a yoke having a transverse wall and a hood portion projecting outwardly from said wall, said hood portion having a forwardly opening aperture defined by an inner concave spherical sur-

face and intermediate concave spherical surfaces spaced from said inner surface, a coupler stem projecting through said aperture adapted to rotate about its longitudinal axis and provided with lateral extensions having surfaces concentric and in bearing relation with said inner concave surface and a rear convex spherical surface in bearing relation with said intermediate concave surfaces, and a bearing block interposed between said coupler stem and transverse wall, said bearing block being provided with an integral dowel extending through a complementary aperture in said transverse wall, thereby retaining said block on the longitudinal axis of said draft rigging.

4. In a railway draft rigging, in combination, a yoke having a transverse web and a two-piece hood portion projecting outwardly from said web, rearwardly extending arms formed integral with said transverse web, a forwardly opening aperture in said hood defined by an inner concave spherical surface, a coupler stem extending through said aperture adapted to move universally with respect to the yoke, lateral extensions on said coupler stem positioned within said hood having surfaces concentric with and engaging said inner concave surface, said lateral extensions being of greater horizontal extent than said forwardly opening aperture, and a bearing block interposed between said coupler stem and transverse web, one of said hood pieces being formed integrally with the web and the other of said hood pieces being removably secured to the first-named piece for enlarging the forwardly opening aperture and facilitating the positioning of said lateral extensions within said hood.

5. In a railway draft rigging, in combination, a yoke having a transverse wall and a two-piece hood portion projecting outwardly from said wall having a forwardly opening aperture, said hood being formed with a portion integral with said transverse wall and a portion detachably secured to said integral portion, said integral portion having downwardly opening slots for the accommodation of shear lugs on said detachable portion, said aperture being defined by an inner concave spherical surface and having a coupler stem extending therethrough, lateral extensions on said coupler stem positioned within said hood and having concentric surfaces engaging said concave surface, and a bearing block interposed between said coupler stem and transverse wall, said coupler stem being adapted to move universally with respect to the yoke.

6. In a railway draft rigging, in combination, a yoke having a transverse member and a hood member projecting outwardly from said transverse member, said hood member having a forwardly opening aperture and an inner concave spherical surface defining said aperture, a coupler adapted to move universally with respect to said yoke having a stem portion projecting through said aperture, said coupler stem being provided with lateral extensions having convex spherical surfaces in bearing relation with said inner concave surfaces, and an arcuate rear portion concentric with said inner concave surfaces, a bearing member provided with a concave spherical surface in bearing relation with the arcuate rear portion of the coupler stem, adjusting means interposed between said bearing member and transverse member, in order to compensate for wear which may result therein from continued use, and means integral with one of said members and engaging one of the other of said mem-

bers for retaining the bearing member on the longitudinal axis of the draft rigging.

7. In a railway draft rigging, in combination, a yoke having a transverse web member and a hood member projecting outwardly from said web member, said hood member having a forwardly opening aperture and an inner concave spherical surface defining said aperture, a coupler adapted for universal movement with respect to the yoke having a stem portion projecting through said aperture and provided with lateral extensions and a rear spherical portion concentric with said inner concave surface, said lateral extensions having convex surfaces in bearing relation and concentric with said inner concave surface, a removable bearing block member provided with a concave surface in bearing relation and concentric with the rear spherical portion of the coupler stem, adjusting means interposed between and in bearing relation with said bearing block member and transverse web member in order to compensate for wear which may result in the connection from continued use thereof, and integral means formed on one of said members for engagement with one of the other of said members for retaining the bearing block member on the longitudinal axis of said draft rigging.

8. A coupler-yoke connection in a railway draft rigging comprising a yoke having a transverse web and a hood portion, a coupler having a stem extending into the hood through a forwardly opening aperture provided in the hood, lateral extensions projecting outwardly of the stem adjacent the rear extremity thereof engaging inner portions of the hood for the transmission of draft forces from the coupler to the yoke, a block arranged to move longitudinally of the draft rigging in bearing relation with the rear extremity of the coupler stem for receiving buffing forces from the coupler, vertically spaced lugs formed integral with said hood for retaining said block in a predetermined position vertically of the draft rigging, a vertically movable wedge interposed between and in bearing relation with the block and web for urging said block longitudinally, and resilient means for retaining the wedge in an elevated position.

9. In a railway draft rigging, in combination, a yoke having a transverse web and a hood portion, a coupler having a stem extending into the hood through a forwardly opening aperture provided in the hood, an enlarged portion provided on the coupler stem adjacent the rear extremity thereof engaging inner portions of said hood for the transmission of draft forces from the coupler

to the yoke, a movable block positioned within the hood in bearing relation with the rear portion of the coupler stem for receiving buffing forces from the coupler, a wedge interposed between and in bearing relation with the block and web for urging said block longitudinally, a bolt extending through the wedge and hood for controlling a downward movement of said wedge, and a spring adapted to retain the wedge in an elevated position.

10. In a coupler-yoke connection for use in a railway draft rigging comprising a yoke having a transverse web and a hood portion, a coupler having a stem extending into the hood through a forwardly opening aperture provided in the hood, lateral extensions projecting outwardly of the stem adjacent the rear extremity thereof engaging portions of the hood for the transmission of draft forces from the coupler to the yoke, a bearing block adapted to move longitudinally of the draft rigging in bearing relation with the rear portion of the coupler stem for receiving buffing forces from the coupler, a wedge interposed between said block and web in order to control the longitudinal movement of the coupler and block with respect to the yoke, a bolt extending through the wedge and hood for urging the wedge downwardly into bearing relation with the block and web, and a spring interposed between the wedge and hood for retaining the wedge in an elevated position.

11. In a coupler-yoke connection for use in a railway draft rigging comprising a yoke having a transverse web and a hood projecting outwardly from said web, a coupler having a stem extending into the hood through a forwardly opening aperture provided in the hood, lateral extensions on said stem adjacent the rear extremity thereof engaging inner portions of the hood for the transmission of draft forces from the coupler to the yoke, a longitudinally movable block in bearing relation with the rear portion of the coupler stem adapted to receive buffing forces from the coupler, a wedge interposed between said block and web for controlling the longitudinal movement of the block, a spring extending within the wedge, and adjustable means for retaining the spring within the wedge, said adjustable means comprising an apertured cap underlying said spring and a pin extending through said cap and an apertured depending web on said hood.
